UNITED STATES PATENT OFFICE.

ALBERT D. HILL, OF OTTAWA, ILLINOIS, ASSIGNOR OF ONE-THIRD TO JOHN POHLIG, OF NEW ORLEANS, LOUISIANA.

RAILWAY-SWITCH-ACTUATING MECHANISM.

SPECIFICATION forming part of Letters Patent No. 592,143, dated October 19, 1897.

Application filed April 5, 1897. Serial No. 630,765. (No model.)

To all whom it may concern:

Be it known that I, ALBERT D. HILL, of Ottawa, in the county of La Salle and State of Illinois, have invented a new and Improved 5 Railway-Switch-Actuating Mechanism, of which the following is a full, clear, and exact description.

This invention relates to mechanism for turning the switch-tongues of railway-tracks; 10 and the object is to provide means whereby the switch-tongues will be automatically operated by devices carried by an engine or car traveling over the rails.

I will describe a switch-actuating mechanism embodying my invention, and then point 15 out the novel features in the appended claims.

Reference is to be had to the accompanying drawings, forming a part of this specification, in which similar characters of reference indicate 20 corresponding parts in all the views.

Figure 1 is a plan view of a switch-operating mechanism embodying my improvement. Fig. 2 is a section thereof on the line 2-2 of Fig. 1. Fig. 3 is a plan view, drawn on an 25 enlarged scale, of a portion of the device; and Fig. 4 is a section on the line 4-4 of Fig. 3.

Referring to the drawings, 1 designates the rails of a main track, and 2 the rails of a switch-track. Arranged at the junction of 30 the main rails and switch-rails are switch-tongues 3, pivoted in the usual manner in a frog. Pivotal connection to the free ends of the switch-tongues 3 is a frame 4, and connected to this frame 4 are rods 5 and 6, and 35 upon each rod 5 and 6 is mounted to swing a dog comprising diverging arms 7 and 8, the arms 8 being designed to engage with the teeth of a rack-bar 9, secured in a depression formed in the track-bed. Of course the shoulder portions of the teeth in the rack-bar will 40 be arranged at opposite directions from the center.

Extended longitudinally of the main track 1 is a horizontally-swinging lever 10, having 45 at one end a pin 11, extended upward through an arc-slot in a covering-plate 12, and designed to be engaged by a part carried by an engine or a car, as will be hereinafter described. This lever 10 has pivotal connection 50 with a lever 13, pivoted between the main

tracks and having arms 14 and 15 extended, respectively, between the main tracks and the switch-tracks. These arms 14 and 15 are provided with pins 16 and 17, extended upward through slot-openings in the covering-plate 55 12. At the junction of the levers 10 and 13 is a tappet comprising two arms 18 and 19, designed to engage with the arms 7 of the swinging dogs.

Carried by the engine or by a car is a shifting lever comprising an upright portion 20, which extends upward into the engine or car, and has a pin portion 21, designed to engage in one of a series of openings in a plate 22, so that the shifting lever will be rigidly 60 held in its adjusted position. The lower end of the shifting lever is provided with a horizontally-disposed portion 23, designed to engage with the pins extended upward from the levers. The shifting lever is designed to rotate, so that it may be shifted to arrange its portion 23 at an angle relatively to the track, in order that the shifting levers of the switch-tongues may be operated in the desired direction. 70

In operation, a train or car approaching the switch will engage the portion 23 of a shifting lever with a pin extending upward from the switch-tongue-shifting levers, and, as this portion 23 is arranged at an angle, it is obvious 75 that the lever 10 or 13, as the case may be, will be swung horizontally, and during this movement the arms 18 or 19 of the tappet carried by the levers will first engage with an arm 7 of a dog, raising the arm 8 out of engagement with the rack 9, and then upon a further movement of the levers the switch-tongues will be shifted to the proper position. 80

It will be seen by the construction of my switch mechanism that the switch-tongues 90 may be operated by a train going at full speed, and, further, that the expense of employing switchmen, signal-lights, and expensive locking devices will be avoided; and above all benefits, the great saving of time 95 by switching at any speed of the car; and, further, the car can enter or leave the switch independently of how the switch may have been left or placed by the preceding car; in fact, the operator turns to the right or left 100

just as the driver of a wagon turns to right or left at will, irrespective of where the preceding vehicle may have gone.

Having thus fully described my invention, 5 I claim as new and desire to secure by Letters Patent—

1. A switch-operating mechanism, comprising switches, a pivotal connection between said switches, levers extended in opposite directions from the switches and pivoted together, a tappet carried by the levers at their connecting-point, swinging dogs each comprising two diverging arms and adapted to be operated by the tappet, a rack for engagement with said dogs, and means carried by an engine or car for swinging the levers on their pivotal points, substantially as specified.

2. In a switch-operating mechanism, switch-tongues pivotally connected one with the other, swinging levers extended in opposite directions from the switch-tongues and having pivotal connection between the switch-tongues, one of said swinging levers having diverging portions, pins extended upward from the ends of the levers, a tappet carried

by the levers at their connecting-point, swinging dogs, each comprising two diverging arms, the inner ones of which are designed to be engaged by the tappet, a rack-bar for engagement with the outer arms of the dogs, and an adjustable shifting lever carried by an engine or car for engagement with the pins extended upward from the levers, substantially as described.

3. A railway-switch, comprising switches, a frame pivotally connected to the switches, rods connected to said frame, dogs mounted to swing on said rods and each consisting of diverging arms, a rack-bar designed to be engaged by the outer arms of the dogs, a horizontally-swinging lever, a tappet carried by said lever and adapted to engage with the inner arms of the dogs to raise the outer arms out of engagement with the rack-bar, a pin extended upward from the lever, and an adjustable shifting lever carried by an engine or car, substantially as specified.

ALBERT D. HILL.
